UNITED STATES PATENT OFFICE.

ROBERT L. DAY, OF HUNTINGTON, WEST VIRGINIA.

BUILDING.

1,420,973.

Specification of Letters Patent. Patented June 27, 1922.

Application filed October 20, 1921. Serial No. 508,924.

To all whom it may concern:

Be it known that I, ROBERT L. DAY, residing at Huntington, in the county of Cabell and State of West Virginia, a citizen 5 of the United States, have invented certain new and useful Improvements in Buildings, of which the following is a specification.

More particularly, my invention relates 10 to building structures, especially dwelling houses, in which blocks, plates, or slabs of cement or other plastic material are used for the roof, and as well for outside walls, partitions, and floors, and my invention has 15 especially to do with the roof construction to the end that the necessary slant or pitch of the roof may be secured while preserving, as far as the external appearance is concerned, a uniform height of the structure 20 and level ceilings, and incidentally to achieve the advantages of an artistic design or appearance of the structure; the efficient and secure bonding together of roof structure and side walls; and the utilization 25 of structural elements capable of rapid and otherwise inexpensive manufacture and assemblage or erection by common or unskilled labor and thereby reduce cost. My invention consists in the construction defined by or included within the scope or 30 meaning of the appended claims.

In the accompanying drawings:

Fig. 1 is a side elevation of a dwelling 35 house embodying my invention;

Fig. 2 is a vertical section from front to rear of the roof and adjacent portions;

Fig. 3 is a detail view in perspective of a portion of the coping.

The house shown in the drawings as an 40 exemplification of my invention is a one-story four-room-and-bath cottage designed with especial reference for use in the coal mining regions, and in constructing the walls, roof, and floor, the reinforced concrete slabs of my Patent No. 1,229,904, June 12, 1917, may be advantageously used and are shown as used in the structure appearing in the drawing, but I do not confine myself to the use of slabs of my patented construction as my invention as set forth in the claims may be embodied in structures whose roof, wall, and floor members may be otherwise made. The walls of the dwelling 50 shown in the drawings are composed of 55 slabs stood on end in two parallel rows with their ribbed faces innermost to provide an air space within them and with their smooth or plane faces outward so that the exterior of the building is smooth and the inner surfaces of the walls within the rooms are 60 smooth.

The roof, 10, in the building shown in the drawings has its top surface sloping downwards from front to back on a gradual incline, but the under surface or ceiling is 65 horizontal or level, which level effect or condition is secured by placing successive portions of the ceiling from front to back in lower planes with the junctions between adjoining sections occurring over a wall as in 70 the case of the junction between the front porch ceiling and the front room ceiling, such portions overlapping above the front wall, 11, or, as in the case of the ceilings of the front and back rooms having the junction above 75 the partition wall, 12. Thus though different portions of the ceiling are in different horizontal planes, the entire ceiling of each room or compartment is level.

Resting upon the tops of the walls is a 80 coping cap, 13, which comprises a horizontal member that rests upon the top surface of the building walls, a vertically extending outer or face member or flange, 14, which projects above and below the horizontal member, and a downwardly projecting member or flange, 15. Said flanges, 14 and 15, are spaced apart a distance equal to the thickness of the wall so that the top portion 85 of the latter is snugly embraced thereby and the slabs forming such are held in position by the coping cap, which is of a length greater than the width of the slabs of which the wall is built. The coping cap extends around all sides of the building, and as the 90 top of the outer or face member 14, is at the same level or in the same horizontal plane all around the building, which is also true of the bottom edge of such member, a finish is provided on the exterior of the building 95 that gives a horizontal appearance at or adjacent the roof notwithstanding the slope of the roof from front to back, and to enable the slope to be given, the horizontal member of the coping cap at the rear wall of the 100 building is in a lower plane than the horizontal member at the front of the building, the planes of such horizontal members being the same as the planes of the ceiling sections contiguous thereto. The outer member or 105 face, 14, may constitute or be a part of a cornice, and if, as shown in the drawings, is

the case, a portion of the roof at the front of the building extends above the horizontal member of the coping cap, there may be a cornice extension, 16, above the same and placed all around the building, such cornice extension being preferably separate from the coping cap and resting upon the top of the latter. The inner flange, 15, of the coping cap is preferably finished off as a molding so as to constitute a mold that appears in the room as a corner finish where wall and ceiling adjoin.

My coping cap is molded or cast of cement or other plastic material, and with or without reinforcement as may be found desirable or necessary, it may be given or made into whatever length or size or proportions or configurations of parts or members which judgment of designer or convenience of manufacturer or user may suggest or dictate. Besides being highly useful in bonding the wall elements to which it is applied; in forming or providing a support for the roof by which the desired slope of the roof is secured while a horizontal ceiling is maintained; and in forming a support for and means of attachment of cornice-like panels, it enables an artistic appearance to be given the structure, and all with a minimum expense in manufacture and erection.

It will be understood that the roof in the case shown in the drawings is formed of slabs, such as those of my before mentioned patent, placed with the ribs uppermost and then covered with a layer of concrete or other material having some desired roof finish applied, the upper surface of the concrete and finish being given the desired slope.

Where partition and division walls occur, a coping is applied to the top thereof with vertical members or flanges of the proper height and configuration to form a cornice-like finish matching that on the inside of the side walls which results from the coping caps applied to the side walls.

It will be seen that by the employment of coping caps in accordance with my invention, the rapid and efficient construction or erection of the building can be accomplished, even when common labor is employed, and the appearance of the finished building, notwithstanding the inexpensive construction, is architecturally good and otherwise pleasing.

55

What I claim is:

1. A building comprising walls, a coping cap for the tops of such walls comprising a horizontal member and spaced inner and outer vertical members, the tops of the outer vertical member being substantially in the same horizontal plane, and the bottoms of the outer member being substantially in the same horizontal plane, and the horizontal member, at different portions of the building, being at different horizontal planes, and a roof supported upon the horizontal members of the coping caps having a sloped upper surface with a ceiling surface formed of sections that are in different horizontal planes but which are level.

60

2. A building comprising walls, a coping cap for the tops of such walls comprising a horizontal member and spaced inner and outer vertical member, the tops of the outer vertical member being substantially in the same horizontal plane, and the bottoms of the outer member being substantially in the same horizontal plane, and the horizontal member, at different portions of the building, being at different horizontal planes, and a roof supported upon the horizontal members of the coping caps having a sloped upper surface with a ceiling surface formed of sections that are in different horizontal planes but which are level, and having a cornice-like extension above and supported by said coping cap.

65

In testimony whereof I hereunto affix my signature.

ROBT. L. DAY.
